Primary Examiner — Vy N Koenig(74) *Attorney, Agent, or Firm* — Dunlap Bennett & Ludwig PLLC(57) **CLAIM**

The ornamental design for a universally adaptable camera mount, as shown and described.

DESCRIPTION

FIG. 1 is a top rear perspective view of a universally adaptable camera mount;

FIG. 2 is a left side elevation view thereof;

FIG. 3 is a right side elevation view thereof;

FIG. 4 is a rear elevation view thereof;

FIG. 5 is a front elevation view thereof;

FIG. 6 is a top plan view thereof;

FIG. 7 is a bottom plan view thereof; and,

FIG. 8 is a front left side perspective view thereof, shown in use.

The broken lines shown in the drawings depict environmental subject matter, specifically connectors and a camera, that form no part of the claimed invention.
